T. J. Knight

Inventor:—

Ó. S. Puffiam.

By Knight, Port
atty's.

UNITED STATES PATENT OFFICE.

OSWALD S. PULLIAM, OF ST. LOUIS, MISSOURI.

CAR-COUPING.

SPECIFICATION forming part of Letters Patent No. 732,441, dated June 30, 1903.

Application filed October 27, 1902. Serial No. 129,030. (No model.)

To all whom it may concern:

Be it known that I, OSWALD S. PULLIAM, a citizen of the United States, residing in the city of St. Louis, in the State of Missouri, have 5 invented certain new and useful Improvements in Car-Couplings, of which the following is a full, clear, and exact description, reference being had to the accompanying drawings, forming part of this specification.

10 My invention relates to improvements in car-couplings, and has for its object the construction of a coupling in which the knuckle-retaining member may be readily moved to disengage it from the tail of the knuckle 15 when strain is exerted thereagainst.

A further object of my invention is to provide a rotatable retaining member by which the tail of the knuckle is swung outwardly on the movement of the member subsequent 20 to its disengagement from the knuckle-tail.

A further object of the invention is to provide a construction by which the knuckle-retaining member will be disengaged from the knuckle-tail in the event of the draw-head 25 becoming disconnected from its fastening, thereby obviating the withdrawal of the coupling from the car and the subsequent deposit thereof on the railway-track, which is liable to cause derailment of car-wheels passing there- 30 over.

The invention consists in features of novelty hereinafter fully described, and pointed out in the claims.

Figure I is a horizontal section of my coupling. Fig. II is a vertical section. Fig. III is a perspective view of the rotatable knuckle-retaining member.

1 designates the draw-bar of the coupling, and 2 its head.

40 3 is the knuckle, having a tail 4.

5 designates a circular cavity in the coupling-head in the path of travel of the knuckle-tail 4.

6 is a crescent-shaped or cam retaining member loosely and oscillatively positioned in the circular cavity 5 and adapted to be rotated vertically in said cavity to engage the knuckle-tail 4. The retaining member is provided with a slot 7, that receives a link 8, 45 which is secured at one end to the member by a pin 9. (See Fig. II.)

50 10 is the crank-arm of a rocking rod, to which

arm the link 8 is connected. The rocking rod is mounted in a bracket 11, mounted on the upper one of a pair of buffer-sills A.

55

The crescent-shaped or cam retaining member is designed to be rotated vertically in the circular cavity 5 and when rotated in the forward direction passes in front of the knuckle-tail, as seen in full lines, Fig. II, thereby carrying the knuckle-tail rearwardly and effectually closing the knuckle. When a strain is exerted upon the knuckle by that of a mating coupler, the force exerted against the retaining member is transverse to the axis of 65 said member, and therefore the member is not rotated by the pressure of the knuckle-tail thereagainst. The retaining member being rotatively positioned in the circular cavity 5 is readily oscillated to free it from engagement with the knuckle-tail and permit the tail to swing forwardly in the opening in the knuckle. A rearward oscillation of the retaining member causes it to be moved so that it will pass into the rear of the knuckle- 70 tail and force the tail forwardly to open the knuckle, so that the parts will assume the positions indicated in dotted lines, Figs. I and II.

The characteristic of merit in my coupler 80 lies in the construction of the parts as described, whereby the knuckle of the coupler will be opened in the event of the coupling draw-bar becoming disconnected from its fastening. In the event of such disconnection 85 the rocking rod being held to the timbers of the car aside from the coupling causes a pull to be exerted upon the link 8 when the coupling moves outwardly on being disconnected from its fastenings, and the retaining member 90 6 is thereby rotated to free the knuckle-tail and permit the separation of the couplers interlocked with each other, so that they will be uncoupled previous to the complete withdrawal of the draw-bar of the coupler and its 95 deposit onto the railway-track to cause by its presence thereon the derailment of the car on which the coupling was previously mounted.

I claim as my invention—

1. In a car-coupling, the combination of a head containing a circular cavity, a knuckle having its tail arranged to traverse said cavity, and a crescent-shaped or cam retain-

100

ing member rotatively positioned in said cavity, substantially as set forth.

2. In a car-coupling, the combination of a head provided with a circular cavity, a knuckle having its tail arranged to traverse said cavity, and a vertically-rotative crescent-shaped or cam retaining member arranged in said cavity and adapted to engage said knuckle-tail, substantially as set forth.

3. In a car-coupling, the combination of a head provided with a cavity interior thereof, a knuckle having a tail arranged to traverse said cavity, a slotted crescent-shaped or cam retaining member rotatively positioned in said cavity free of pivotal connection to the

surrounding head, and means for rotating said member, substantially as set forth.

4. In a car-coupling, the combination of a head provided with a circular cavity on the interior thereof, a knuckle having a tail arranged to traverse said cavity, a crescent-shaped or cam retaining member positioned in said cavity, and means carried by the car for rotating said member, substantially as and for the purpose set forth. 20

OSWALD S. PULLIAM.

In presence of—

NELLIE V. ALEXANDER,
M. P. SMITH.
